ATTACHMENT FOR SEWING MACHINES

George H. Galbraith, New York, N. Y.

Application July 7, 1931. Serial No. 549,191

8 Claims. (Cl. 112—141)

This invention relates to new and useful improvements in a hemmer attachment for sewing machines.

The invention relates more particularly, to a hemmer attachment capable of turning the edge of cloth substantially $1\frac{1}{4}$ times around elastic tape and feeding it in this manner to the sewing machine. The invention particularly proposes an arrangement whereby the tape within the rolled edge of a guide can be moved slightly laterally at will to cause the sewing machine to stitch through the elastic tape whenever this is required.

It is old to construct a hemmer which encases elastic tape and to make a provision whereby the elastic together with the entire cloth guiding member may be moved laterally for causing the stitches of the sewing machine to stitch it down upon the material whenever this is desired. But in all of these prior devices it was necessary to encase the tape by bending over the edge of the material, then guiding the tape over the edge and finally supplying a strip of covering material over the elastic tape. When thus constructed, it is quite easy to reach in between the materials about the tape and move the tape laterally.

This invention proposes particularly moving the tape laterally when completely enveloped in the edge of the cloth by reason of the cloth being turned at least $1\frac{1}{4}$ times.

As another one of the objects of this invention, it is proposed to provide a guide having a member for curling cloth substantially $1\frac{1}{4}$ times around elastic tape guided through the center of the member, an arm pivoted on the guide and extending into the curling member from the rear to the front for moving the tape at the center of the guide, and a means for moving the pivoted arm.

The invention has for a still further object the construction of a hemmer attachment for sewing machines which is of simple, durable construction, dependable in use and efficient in action, and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a plan view of a hemmer attachment according to this invention.

Fig. 2 is a front elevational view of Fig. 1.

Fig. 3 is a bottom view of Fig. 2.

Fig. 4 is an enlarged fragmentary elevational view looking in the direction of the line 4—4 of Fig. 1.

Fig. 5 is a fragmentary sectional view, taken on the line 5—5 of Fig. 2.

The hemmer attachment, according to this invention, comprises a body in the form of a plate having a vertical portion 10 integral with a top horizontal portion 11 at right angles to the vertical portion. A slide or carriage 12 is arranged upon the corner between the vertical and horizontal portions. This slide has a horizontal top portion 13 immediately adjacent the horizontal portion 11 of the body and a vertical side portion 14 immediately adjacent the vertical portion 10 of the body. A screw 15 engages through a slot 16 in the vertical portion 14 of the slide and threaded into the vertical portion 10 of the body. This screw, together with a pair of screws 17 which engage through a slot 18 in the horizontal portion 13 and threaded into the horizontal portion 11, serve to hold the slide 12 in a slidable condition. A plate 19 is engaged under the heads of the screws 17 and is of a greater width than the slot 18.

A bell crank 20 is pivotally mounted by a screw 21 upon the vertical portion 10 of the body and has one of its ends connecting with a link 22 which also connects with the slide 12. The intention is that the other arm of the bell crank 20 connects with suitable linkage which terminates in the foot pedal so that the operator of the sewing machine may pivot the bell crank to cause moving of the slide and corresponding moving of the tape as hereinafter fully set forth. A hook 23 is attached upon the vertical portion 10 of the body and another hook 24 is attached upon the slide 12. A tension spring 25 is engaged between these hooks and normally holds the slide 12 in a retracted position.

A tension means is provided whereby the tension at which the tape may be fed through the cloth guiding member can be adjusted. This tension means comprises a plate 26 movably mounted upon screw 27 projecting from the vertical portion 10. A stud 28 projects from the vertical portion 10 through an aperture in the plate 26 and a coaxial spring 29 is arranged upon the stud adjustable to various tensional stresses by a thumb nut 30 on the stud. A pair of guide pins 31 project from the vertical portion 10 and serve to limit motion of the plate 26 laterally only. A tongue 32 is bent off from one

edge of the plate and is engageable by the end 33 of an arm adjustably mounted on the vertical portion 14 of the slide. This latter mentioned arm has a slot 34 through which screws 35 pass.

5 These screws are threadedly engaged into the slide 12. The tape indicated on the drawing by reference numeral 36 passes between the plate 26 and the vertical portion 10.

A cloth guiding member 37 has a projecting 10 lug 38 formed with slots 39 through which screws 40 pass. These screws engage threadedly into the horizontal portion 11 of the body for holding the guide in fixed position on the body. The details of the guide 37 will not be gone into entirely since such guides are generally known. Suffice it to say, that one edge of the guide is rolled around at the portion indicated at 41 and another member 42 attached on the guide and also rolled around in a manner so that cloth may 15 be passed through the guide and encircle the tape 36 at least $1\frac{1}{4}$ times. A slot 43 in the top of the guide 37 allows the tape to pass up into the top side of the guide whereupon another slot 44 allows it to pass immediately under the top 20 side through the various turns 41 and 42.

The main feature of this invention comprises 25 an arm 45 which is flat against the under side of the guide 37 and pivotally mounted by a screw 46. The arm 45 extends through the turns of the cloth guiding mechanism from the rear to the front at the point where the tape discharges from the guide. At the front portion, the arm 45 is enlarged and bent upon itself, indicated by 30 numeral 47, so as to be of substantially oval form as clearly shown in Fig. 4. This enlarging and bending forms a short tube on the end of the arm 45 which carries the elastic tape and which is capable of moving the tape laterally. The arm 45 has an extension 48 on the opposite side of the 35 pivot 46 and a spring 49 acts between the extension 48 and the underside of the guide member 37 for normally pivoting the arm 45 into its neutral or operating position. A finger 50 is adjustably mounted upon the slide 12 by reason of 40 screws 51 engaging through a slot 52 in the finger and threadedly into the horizontal portion 13 of the slide.

This finger 50 has an end portion 53 bent at right angles and acting against one side of a pin 54 projecting from the bottom of the extension 48. The pin 54 is also engaged by spring 49 which acts against its opposite side to cause the pivoting of the arm 45. The spring 49 is shown wound around a peg 55 in the underside of the 55 guide 37 and ending in an aperture formed in the guide member.

The operation of the device consists in operating the bell crank 20 to cause the slide 12 to move for simultaneously releasing the tension of 60 the tape 36 by reason of lifting up the plate 26 and pivoting the arm 45 for moving the tape laterally within the cloth guide. The cloth which is intended to be placed within the cloth guide is not shown in the drawing since this part of 65 the disclosure forms no part of the invention and is generally known. When this cloth is engaged upon the guide 37 it will encircle around the tape which runs through the turns of the guide. As the arm 45 moves laterally, the oval shaped portion 47 of the arm will move the tape correspondingly laterally. When the bell crank 20 is released 70 the plate 26 will move back to its original position to again tension the tape.

While I have shown and described the preferred 75 embodiment of my invention, it is to be under-

stood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A hemmer attachment for sewing machines, comprising a guide having a member for curling the edge of cloth substantially $1\frac{1}{4}$ times around an elastic tape passed through the guide, a pivoted arm on said guide extending into the curling member from the rear to the front for moving the tape laterally, a spring acting between the arm and the guide for urging said arm into an operative position and means for moving said pivoted arm.

2. A hemmer attachment for sewing machines, comprising a guide having a member for curling the edge of cloth substantially $1\frac{1}{4}$ times around an elastic tape passed through the guide, a pivoted arm on said guide extending into the curling member from the rear to the front for moving the tape laterally, and means for moving said pivoted arm, said pivoted arm having an extended portion, and resilient means acting between said extended portion and a stationary portion of the device for urging the pivoted arm into an operative position.

3. In a hemmer attachment for sewing machines, a guide having a member for curling the edge of cloth substantially $1\frac{1}{4}$ times around an elastic tape passed through the guide, an arm pivoted intermediate of its ends upon said guide and one of the ends of said arms extending into the curling member from the rear to the front for moving the tape laterally, and means for moving said pivoted arm, comprising a pin projecting from the other of the ends of the said arm, and means for acting against said pin.

4. In a hemmer attachment for sewing machines, a guide having a member for curling the edge of cloth substantially $1\frac{1}{4}$ times around an elastic tape passed through the guide, a pivoted arm on said guide extending into the curling member from the rear to the front for moving the tape laterally, and means for moving said pivoted arm, including a pin projecting from an extension of said pivoted arm, and a movable finger with an offset end acting against said pin.

5. In a hemmer attachment for sewing machines, a guide having a member for curling the edge of cloth substantially $1\frac{1}{4}$ times around an elastic tape passed through the guide, a pivoted arm on said guide extending into the curling member from the rear to the front for moving the tape laterally, and means for moving said pivoted arm, comprising a slide means for moving said slide, a finger extending from said slide and having an offset free end, a pin in the path of motion of said finger and mounted upon an extension of said pivoted arm, and resilient means urging said pivoted arm into one position.

6. In a hemmer attachment for sewing machines, a body, a guide having members for curling the edge of cloth substantially $1\frac{1}{4}$ times around an elastic tape passed through the guide, and means for simultaneously moving the tape laterally and releasing the tension of the tape, comprising an arm pivotally mounted upon the guide for laterally moving the tape, a plate attached to the body and pressing the tape to the body for tensioning the tape, and means for si-

- multaneously moving the arm and lifting the plate.
7. In a hemmer attachment for sewing machines, a body, a guide having members for curling the edge of cloth substantially $1\frac{1}{4}$ times around an elastic tape passed through the guide, and means for simultaneously moving the tape laterally and releasing the tension of the tape, comprising an arm pivotally mounted upon the
- 10 guide for laterally moving the tape, a plate attached to the body and pressing the tape to the body for tensioning the tape, and means for simultaneously pivoting the arm and lifting the plate, comprising a carriage slidably mounted
- 15 upon the body and means attached to said carriage for moving the arm upon sliding of the carriage, means attached upon said carriage for lifting the said plate upon sliding of the carriage, and means for sliding the said carriage.
- 20
8. In a hemmer attachment for sewing machines, a guide having a member for curling the edge of cloth substantially $1\frac{1}{4}$ times around an elastic tape passed through the guide, an arm pivoted intermediate of its ends upon said guide and one of the ends of said arm extending into the curling member from the rear to the front for moving the tape laterally, and means for moving said pivoted arm, comprising a pin projecting from the other of the ends of the said arm, and means for acting against said pin, comprising a peg fixed in the said guide, and a spring wound around the peg intermediate of its ends, one end of said spring engaging in an aperture formed in the guide, the other end of said spring engaging the pin.
